(57) **CLAIM**

The ornamental design for dumbbell rest, as shown and described.

DESCRIPTION

FIG. 1 is a perspective view of a dumbbell rest, showing my new design;

FIG. 2 is a top plan view thereof;

FIG. 3 is a rear elevational view thereof;

FIG. 4 is a bottom plan view thereof; and,

FIG. 5 is a right side elevational view thereof, wherein the left side elevational view is a mirror image thereof.

The broken line portions of the disclosure are for illustrative purposes only and form no part of the claimed design.
